UNITED STATES PATENT OFFICE.

LEWEN R. NELSON, OF PEORIA, ILLINOIS.

SPRINKLER.

Application filed June 9, 1924. Serial No. 718,723.

This invention has reference to lawn sprinklers. More particularly, it pertains to that type of device having a single relatively large discharge opening in the top of a low 5 sprinkler-body, and of such a construction that water will be made to take up a swirling spiral motion and issue in a spray at such opening.

The object of my invention is to provide a 10 novel construction that can be easily produced at a low cost by means of metal stampings wherein the described action can be realized and by which better results can be produced in the action of the device.

15 To the end that the invention may be understood, the appended drawing is furnished wherein—

Figure 1 is a vertical section of my improved 20 sprinkler taken through the center thereof.

Figure 2 is a plan of the same, part of the top being shown broken away to show interior construction.

Figure 3 is an elevation of the inner end 25 of a nut shown in the first two figures, and

Figure 4 is a transverse section of the same on line 4—4, Figure 2, as seen at its opposite end.

I am well aware of the fact that 30 sprinklers that throw from an opening therein a funnel-shaped spray by an interior whirling action of water are not new but my device is much more simple in construction, can be made in lighter form, since I am enabled to produce it from stamped metal, it can be produced at a low cost, and in operation better spraying and consequent sprinkling is possible.

The character 1 denotes the body of the 40 sprinkler as a whole. It comprises or may have any suitable form so long as the results to be described herein can be attained. In the present instance, however, said body includes an inwardly and downwardly dished top 2 and a side wall 3 of circular form, in plan, or as seen in Figure 2. Centrally of the top is a discharge opening 4 which preferably, of course, lies in a plane lying parallel to the base of the body as it rests 45 upon the ground. Attached to the wall at the base thereof is an inwardly concave bottom section 5 whose marginal edge is rolled over upon the marginal edge of said wall to form a water-tight joint as at 6.

50 A portion of the wall 3 at 3' is preferably formed substantially perpendicularly to the

base of the body and has an opening 7 whose axis is in line with the center of the hole or opening 4 of the top, and this receives into it a "nut" 8 for engagement with a hose fitting 9, for example, Figure 2. Said nut is a stamping having formed near one end a flange 10, created by folding the metal wall upon itself which flange in assembling the 55 sprinkler is abutted upon the inner side of the wall-portion 3', the outer projecting end of said nut being forced down upon the outer wall-surface as at 11 whereby to securely hold said nut and form a water-tight connection. The inner end of the nut is 60 closed by an end wall 12 which, however, is provided with a substantially semi-circular slit by severing the metal partially, creating a tongue or deflector 14 most clearly shown in the last three figures of the drawing, said 65 deflector being bent inwardly or toward the center of the body as clearly indicated in Figure 2. While the nut and its member 14 may be made otherwise than of a stamping the latter is to be preferred from the standpoint of rapid production and accuracy of 70 form.

Any usual gasket or packing-ring 15 is 75 interposed between the end of the hose fitting 9 and the end portion 12 outside the slit and deflector to make a water-tight joint yet permitting free flow of the water upon the said deflector and its entry into the body.

The water under pressure as it flows into the body is naturally deflected by the member 14 and caused to partake of a rotary motion, following the wall 3, finally issuing 80 from the opening 4 in a spray in the form of an inverted cone.

85 Sprinklers of this type of which I am aware have usually been made in the form of a heavy casting which is quite bulky of necessity, the metal at the opening corresponding to 4 herein being quite thick so that with a given diameter of opening which 90 must always be of a size small enough to maintain a proper pressure within the body, the cone shaped water-discharge is thrown quite high and falls too close to the device to permit a large area to be sprinkled at one 95 time. However, in forming the body of a stamping the walls of the opening 4 are quite thin by comparison and as a result the spraying cone of water is thrown at a much lower 100 angle and consequently quite far from the device and therefore a much larger area can 105 be covered than would otherwise be the case 110

and in consequence a given territory may be sprinkled in shorter time.

The member 14 may be adjusted to such position that any desired bulk of stream 5 may be admitted to the body and the incoming stream may be gauged to the area of the discharge opening as found best suited to the results desired.

I may make use of an eyelet 16 within 10 the opening 4 as shown in Figure 1 which although appearing of some considerable thickness in the drawing can really be quite thin so as not to defeat the advantages named with respect to a low angle of spray- 15 throw. Should the body be made of a metal, such as steel for example, an eye of copper or brass which is relatively non-cor- 20 rodible may be employed, the edges of the eye being made to enclose the body, and at 25 said opening to protect it from corrosion.

I claim:

1. In combination with a sprinkler head including side and top walls and having a single central discharge orifice in said top 25 wall, a nut secured in the side wall of the head, the axis of whose bore is disposed at right angles to the axis of said orifice, both axes lying in the same plane, a wall at the inner end of said nut lying within the space 30 of said head and at right angles to the axis of the bore of the nut, said wall being integral with said nut and arranged parallel to the axis of the discharge orifice, said wall being slotted and a portion adjacent 35 the slit being bent outwardly to deflect the stream passing through said slit at an angle to the bore of the nut toward the sides of the head.

2. In combination, a sprinkler head including top and side walls and having a single central discharge orifice in said top 40 wall there being an opening in the side wall,

a nut in said opening the axis of whose bore lies in the same plane with the axis of the said orifice, said nut having a circumferential flange adapted to seat upon the inner side of the wall at said opening, 45 said nut having a free end extending outward from said flange outside the wall adapted to be spread and clamped upon the 50 opposite side of the wall to enclose the metal at said opening between said end and said flange, said nut having an integral wall at its inner end substantially at right angles to the axis of its bore extending into the 55 sprinkler head and slotted and a portion adjacent the slit being bent outwardly at an angle to deflect a water stream at an angle to the bore of the nut in passing through said slit, and toward the sides of 60 said head.

3. In combination with a sprinkler head including a top wall having a central discharge orifice and a side wall having an opening opposite the center of the body, a 65 threaded nut formed from a ductile metal seated in the said opening the axis of whose bore lies in the same plane with the axis of the orifice, said nut having flanges at one end, one at each side of the said side 70 wall adapted to clamp said wall between them, said nut also having a wall at its other end lying within the body in a plane at right angles to the bore of the said nut adapted to receive a packing ring upon 75 it, said wall inward from the portion receiving said ring being partially severed to create a deflecting member, said member being extended into the body at an angle to the axis of the said bore adapted to direct 80 a water stream toward side walls of said body.

In testimony whereof I affix my signature.
LEWEN R. NELSON.
